UNITED STATES PATENT OFFICE

93,142

DESIGN FOR A JAR

Frasier Smith, Wheeling, W. Va., assignor to Holsum Products, Inc., Milwaukee, Wis., a corporation of Wisconsin

Application June 15, 1934, Serial No. 52,197

Term of patent 7 years

To whom it may concern:

Be it known that I, FRASIER SMITH, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a perspective view of a jar showing my new design; and

Figure 2 is a similar view taken from a different angle thereof.

I claim:

The ornamental design for a jar, as shown.

FRASIER SMITH.
